(57) **CLAIM**

The ornamental design for a four-sided post extrusion for mounting panels, as shown and described.

DESCRIPTION

FIG. 1 is a perspective view of a four-sided post extrusion for mounting panels showing the new design; FIG. 2 is a left elevational view thereof; FIG. 3 is a front elevational view thereof; FIG. 4 is a right elevational view thereof; FIG. 5 is a back elevational view thereof; FIG. 6 is a first end view thereof; FIG. 7 is a second end view thereof; FIG. 8 is a perspective view of a second embodiment of a four-sided post extrusion for mounting panels showing the new design; FIG. 9 is a left elevational view thereof; FIG. 10 is a front elevational view thereof; FIG. 11 is a right elevational view thereof; FIG. 12 is a back elevational view thereof; FIG. 13 is a first end view thereof; and, FIG. 14 is a second end view thereof.

The broken lines showing environment in the drawings are included for illustrative purposes only and form no part of the claimed design.
